UNITED STATES PATENT OFFICE

FRANK W. HOBART, OF CHELSEA, MASSACHUSETTS

GARMENT ATTACHMENT

Application filed February 2, 1931. Serial No. 512,861.

This invention relates to means for holding the looped strip material of garment attachments in any condition of effective length, and has particular reference to garment or hose supporters, garters, armlets, suspenders and the like.

Articles of the character referred to usually include straps or strips of flexible material, each having a loop portion the length of which is to be varied to meet the requirements of the individual wearer, a take-up attachment being included in the article to enable the length of the loop to be adjusted.

An objection to the employment of take-up attachments having toothed strap-gripping members is that the teeth thereof cause undue wear and mutilation of the strap that is engaged thereby. And an objection to that type of article which employs take-up attachments having strap-engaging members that are straight so as to clamp the strap without forcing any portion of it into the strap, is that careless handling, especially if the article is dropped on the floor, frequently results in such opening or parting of the gripping members that the desired adjustment of the loop is no longer maintained. And an objection to that type of article which employs a single flat plate having two slots each of which must accommodate two thicknesses of the strap or strip, is that adjustment of the length of the loop is a rather tedious operation.

The object of my invention is to provide garment articles of the character referred to, having easily operated strap-gripping members which, although straight and toothless from end to end, will reliably remain in gripping relationship even when carelessly handled, but can be easily opened when necessary to effect an adjustment.

With said objects in view, the invention consists in the construction and combination of parts substantially as hereinafter described and claimed.

45 Of the accompanying drawings:—

Figure 1 is a front view of my improved take-up attachment in one of its positions to maintain a portion of a flexible strip in the form of a loop.

50 Fig. 2 is a side elevation of the same.

Figure 3 is a front elevation of the take-up device alone.

Figures 4 and 5 are sectional views illustrating the closed and opened positions respectively of the jaws of the take-up device. 55

Similar reference characters designate similar parts or features in all of the views.

The illustrated strip 12 of flexible material may be a portion of an ordinary leg-surrounding garter band, or a similar looped 60 portion of any other garment attachment. The take-up device for the loop, which device will, for the sake of brevity, be hereinafter referred to as the clasp, comprises two members of suitable metal. One member 13 is 65 slotted to provide a cross bar 14 to which one end of the strip 12 is connected and is formed with an edge 15 which constitutes one of the strip-gripping jaws. Said edge of jaw 15 is smooth from end to end, or, in other words, 70 has no teeth. The side margins of the member 13 are bent to provide eyes 16.

The other member 17 of the device is slotted to provide a cross bar 18 mounted in the eyes 16 of the member 13, and is formed 75 with an edge or jaw 19 which is also smooth from end to end to coact with the jaw 15 in gripping the strip 12.

The important feature of my invention resides in the member 17 having a knob or projection 20 in such position that, when the opposing jaws 15, 19, are gripping the strip (see Fig. 4) said knob exerts pressure to hold 80 a small area of the strip bent partly around the edge of the jaw 15. In other words, the construction is such that, when the member 17 is rocked relatively to the member 13, the inner surface of the knob 20 slightly passes 85 the edge of the jaw 15 at a distance therefrom less than the thickness of the strip so that, when the members are shifted from the position illustrated by Fig. 5 to the position illustrated by Fig. 4, the knob 20 temporarily compresses a small area of the strip and 90 snaps over the jaw 15 to a position where it remains due to the presence of a small area of the strip between said knob and jaw. This locked position of the two members is sufficiently reliable to prevent accidental opening 95 of the jaws. But, when it is desired to

100

open the jaws, as when the length of the loop of the strip 12 is to be adjusted, the same knob 20 facilitates such opening by engaging one's finger or finger nail with it and pressing it down below the jaw 15 to the position illustrated by Fig. 5. When the parts are in the last-mentioned position, it is very easy to slide the strip 12 lengthwise so as to vary the length of its looped portion and then a simple closing operation returns the jaws to strip-gripping positions. When the device is in use, the stronger the pull is on the strip 12, the more firmly the jaws 15, 19 maintain their gripping relation on the strip. This is due to the fact that the pull tends to force the knob 20 firmly to the position where it bears on the strip and presses the latter on to the outer surface of the jaw 15.

By the hereinbefore reference to jaws being smooth-edged, I mean that the jaws have no such teeth as would tend to unduly injure the flexible strip.

Having now described my invention, I claim:

1. A buckle comprising two pivotally connected frame members, each frame member having a passage to receive a strip of flexible material, a jaw on each member arranged to coact with the other jaw to grip such strip, said passages being arranged at opposite ends of the buckle when such strip is gripped thereby, and locking means on one frame member positioned to snap over the outer edge of the jaw of the other member and a portion of the strip engaged by said edge to hold the jaws in strip-gripping relationship.

2. A buckle comprising two pivotally connected frame members, each frame member having a passage to receive a strip of flexible material, a straight-edged jaw on each member arranged to coact with the other jaw to grip such strip, said passages being arranged at opposite ends of the buckle when such strip is gripped thereby, and locking means projecting from the straight-edge jaw of one frame member positioned to snap over the outer edge of the jaw of the other member and a portion of the strip engaged by said edge to hold the jaws in strip-gripping relationship.

3. A buckle for gripping a strip of flexible material, said buckle comprising two members one of which is slotted and has a straight smooth-edged jaw with eyes at the ends of said jaw, the other member of the clasp being pivotally mounted in said eyes and having a straight smooth-edged jaw close to the jaw of the first-mentioned member and having a knob a portion of which is positioned to snap over and lockingly receive the other jaw and a portion of the strip between said jaws.

In testimony whereof I have affixed my signature.

FRANK W. HOBART.
